UNITED STATES PATENT OFFICE

THOMAS FARRELL, OF DUBUQUE, IOWA.

CAR-COUPING.

SPECIFICATION forming part of Letters Patent No. 243,538, dated June 28, 1881.

Application filed May 19, 1881. (Model.)

To all whom it may concern:

Be it known that I, THOMAS FARRELL, of Dubuque, in the county of Dubuque and State of Iowa, have invented a new and valuable 5 Improvement in Car-Couplers; and I do hereby declare that the following is a full, clear, and exact description of the construction and operation of the same, reference being had to the annexed drawings, making a part of this 10 specification, and to the letters and figures of reference marked thereon.

Figure 1 of the drawings is a representation of a top view of my invention. Fig. 2 is a side view, and Fig. 3 is a longitudinal section, of 15 the same.

This invention has relation to improvements in means for coupling cars, and has for its object the production of a device whereby the cars can be readily and automatically coupled. 20

The invention consists in the construction and novel arrangement of parts, hereinafter described, and especially pointed out in the claims.

In the accompanying drawings, the letter *a* designates an open-top draw-head having an 25 upwardly-beveled lower lip, *b*, in which are made two notches, *c* and *d*, side by side, the former having shoulders *c'* in front.

Extending back from the lip is a wall, *e*, on 30 the sides of which are the channels *f* and *g*, which terminate at the lip *b*, forming shoulders *f'* and *g'* back of said lip, the notches *c* and *d* running into these channels, but having their bottoms above those of the latter, so that the 35 shoulders *p'* and *g'* are formed.

Located in the channel *f*, and rising from the side of the draw-head, is a bearing, *h*, parallel to the tongue *e*, and between said bearing and tongue is pivoted by a bolt, *h'*, the coupling- 40 hook *k*. The coupling-hook projects beyond the draw-head, its rear end, *k'*, fitting the groove or notch *c*, and having shoulders *k''*, corresponding in position to the shoulders *c'*. The rear portion, *k'*, of the coupling-hook is forked at 45 its forward end, forming bearings *k'''*, between which the front portion, *l*, of the coupling-hook is pivoted. A recessed bearing or stop, *k''*, is provided under the broad or forked end of the rear portion, *k'*, in which the rear end of the 50 front portion, *l*, of said hook is received when

said hook is extended in working position. The forward end of the front of the coupling-hook is provided with the beveled head *m*, having the rear shoulders, *m'*, being adapted in form to engage the shoulders in rear of the lip of 55 the opposite draw-head, which is designed to be of similar construction. The coupling-hook being jointed in the manner described, its front or catching portion can be raised and held back to prevent coupling when desired; or it 60 can be set against a bearing, *z*, on the rear part, *k'*, so that when the cars come together it will fall forward into engagement with the opposite draw-head. Provision is also made for using the ordinary pin-and-link coupling 65 by forming in the lip *b* the ordinary mouth and pin-opening, as indicated in the drawings.

Extending transversely through the draw-head is arranged the operating crank-shank *n*, having the elongated crank *n'*, which is connected to the coupling-hook. This operating-shaft is also provided with exterior handles, *n''* 70 *n'''*. There is also formed on said shaft, outside the draw-head, a crank-loop, *p*, having a shoulder or bearing, *p'*, next the wall of the 75 draw-head. The crank-loop *p* extends forward, and below it is pivoted to the wall of the draw-head a dog, *H*, having its upper edge beveled or rounded, and provided with a pin, *q*, a little forward of its pivot. A link-connection, *r*, 80 extends from the crank-loop *p* to the pin *q*. This construction is designed to throw the dog *H* under the bearing *p'* of the shaft when the latter is turned backward, thereby holding up 85 the coupling-hook. A guide-bearing, *s*, is provided on the outside of the draw-head, in front of the lower portion of the dog *H*, and a slide-bar, *w*, is arranged therein. Said bar is designed to have sufficient length to project in front of the draw-head, and is provided with 90 a stop-slot, *s'*; and pin *v*, to limit its movement. When the draw-heads of opposite cars come together the projecting end of the slide-bar will become engaged, and said bar will be pushed back, its rear end striking the lower portion 95 of the dog *H*, which will thereby be moved from under the bearing of the crank-shaft, so that the hook will be allowed to drop and become engaged with the opposite draw-head.

In some constructions it may be advisable 100

to make the coupling-hook without a joint. I do not, therefore, desire to be confined to the employment of the jointed coupling-hook.

Having described this invention, what I claim, and desire to secure by Letters Patent, is—

1. The jointed coupling - hook having the forked rear portion, k' , the recessed bearing under the forked end thereof, and the front or catching portion, l , pivoted to the rear portion, substantially as specified.
2. The combination, with a draw-head and

its coupling-hook, of the transverse operating-crank-shaft n , the crank-loop p , bearing p' , link r , dog H , and slide-bar w , substantially as specified.

In testimony that I claim the above I have hereunto subscribed my name in the presence of two witnesses.

THOMAS FARRELL.
